BAKER & WILHELM CO. P. A.

UNITED STATES PATENT OFFICE.

CHRISTIAN WEYAND, OF BUFFALO, NEW YORK.

GUN-MUZZLE PROTECTOR.

1,258,283.

Specification of Letters Patent. Patented Mar. 5, 1918.

Application filed September 28, 1917. Serial No. 193,734.

To all whom it may concern:

Be it known that I, CHRISTIAN WEYAND, a citizen of the United States, residing at Buffalo, in the county of Erie and State of New York, have invented certain new and useful Improvements in Gun-Muzzle Protectors; and I do hereby declare the following to be a full, clear, and exact description of the invention, such as will enable others skilled in the art to which it appertains to make and use the same.

This invention has for one of its objects the provision of a device of this character, whereby the bore of a gun barrel will be protected from foreign matter entering therein.

Another object of this invention is the provision of a closure member pivotally supported on the barrel of a gun and adapted to overlie the bore thereof to prevent dirt and other foreign matter from entering the bore.

A further object of this invention is the provision of means whereby the device may be readily and conveniently applied to the barrel of a gun.

A still further object of this invention is the provision of a gun muzzle protector of the above stated character, which shall be simple, durable and efficient, and which may be manufactured and sold at a comparatively low cost.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which:

Figure 1 is a side elevation of a gun muzzle protector, constructed in accordance with my invention.

Fig. 2 is a top plan view of the same.

Fig. 3 is a transverse sectional view taken on the line 3—3 of Fig. 1,

Fig. 4 is an end elevation of a modified form of my invention.

Referring in detail to the drawing, the numeral 1 indicates as an entirety, a clip consisting of a body portion 2 having formed thereon, extensions 3 that are apertured to receive a bolt 4 for securing the

clip 1 about a gun barrel 5 adjacent the muzzle thereof. The body 2 has formed thereon upwardly extending ears 6, which ears are apertured to receive a bolt 7. The bolt 7 has also journaled thereon, ears 8, which are formed upon an extension 9 carried by a closing member or element 10 that is adapted to normally overlie the bore of the gun barrel 5 to prevent dirt and other foreign matter from entering the bore.

A coiled spring 11 is wound about the bolt 7 and has one end secured to the body 2 as at 12, while its opposite end is secured to the extension 9 for the purpose of normally holding the closing member 10 in engagement with the end of the gun barrel 9 so that foreign matter will be prevented from entering the bore thereof.

When the gun is fired, the air which is forced out of the gun barrel by the bullet swings the closing member 10 upon its hinge or pivot so that the same will be disposed out of the path of the bullet and will not deflect or interfere with the line of travel of the bullet.

Referring to my modified form of invention which is especially adapted for use upon guns having comparatively large barrels, it consists of a clamp 13 that is secured about the barrel of the gun adjacent the muzzle thereof by a set screw 14 passing through relatively spaced ears or projections 15. The clamp 13 has formed thereon pairs of oppositely disposed ears 16 which are apertured to receive bolts 17. The bolts 17 have journaled thereon relatively spaced ears 16 formed upon semi-circular closing members 19. The semi-circular closing members 19 are adapted to swing toward each other over the muzzle of the gun to completely close the bore and when in contact with each other form a complete circular closing plate. Surrounding the bolts 17 are coil springs 20 which have one of their ends secured to the ears 16 and the opposite ends disposed against the closure plate for the purpose of normally swinging the closure plates in the direction toward each other and over the bore of the barrel of the gun so as to prevent dirt and other foreign matter from entering the gun and which will permit the projectiles to escape from the bore when the gun is fired, owing to the pressure of air against said members as the projectile passes through the bore of the barrel of the gun.

While I have shown and described the preferred embodiment of my invention, it will be understood that minor changes in construction, combination and arrangement 5 of parts may be made without departing from the spirit and scope of the invention as claimed.

What is claimed is:—

- 10 1. A gun muzzle protector comprising a clip secured to a gun barrel, upwardly extending ears formed on said clip, a bolt carried by said ears, ears carried by said bolt, an extension formed on said last named ears, a closure member formed on the extension and adapted to overlie the bore of the gun barrel, and a coiled spring wound about the bolt and having one end secured to the clip
- 15

and its other end disposed against the extension for normally holding the closure member over the bore of the gun barrel. 20

2. A gun muzzle protector comprising a clamp secured to the barrel of a gun, pairs of oppositely disposed ears formed on said clamp, semi-circular members pivoted to said ears and adapted to close the bore of the 25 gun, and springs for normally urging the closure members in the direction of each other over the bore of the gun.

In testimony whereof I affix my signature in presence of two witnesses.

CHRISTIAN WEYAND.
